UNITED STATES PATENT OFFICE.

ANTONIO PENTIFALLO, OF HOLLIDAYSBURG, PENNSYLVANIA.

RUBBER HEEL.

Application filed August 21, 1923. Serial No. 658,559.

This invention relates to lifts for shoe heels and has particularly reference to those constructed of resilient material.

An important object of the invention is to provide various forms of shoe heel lifts which are constructed from resilient material and adapted for more accurately fitting the heel base of a shoe.

Other objects and advantages of the invention will be apparent during the course of the following description.

In the accompanying drawings forming a part of this specification and in which like numerals are employed to designate like parts throughout the same,

Figure 1 is a side elevational view, partly in section, of a shoe heel with a lift partially in place thereupon,

Figure 2 is a similar view to that shown in Fig. 1 with the lift entirely in place thereupon,

Figure 3 is a top plan view of a heel lift embodying this invention,

Figure 4 is a rear elevational view of the left shown in Fig. 3,

Figure 5 is a front elevational view of the lift shown in Fig. 3,

Figure 6 is a top plan view of a modified form of a shoe lift embodying this invention,

Figure 7 is a top plan view of a still further modified form of a shoe lift.

In the drawing, wherein for the purpose of illustration is shown a preferred embodiment of this invention, the numeral 5 indicates a shoe heel of any well known form that is properly attached to the shoe upper designated by the numeral 6.

Referring particularly to Figs. 1 to 5 inclusive there is shown a heel lift generally designated by the numeral 7 that is adapted for being attached to the shoe heel 5 in the manner shown in Figs. 1 and 2. This heel consists primarily of a substantially centrally positioned flat portion 8 that is in the form of a parallelogram and is more distinctly outlined upon the upper face of the lift or, in other words, upon the face that is to be positioned against the under face of the shoe heel. The bordering edges 9 of this flat portion are formed integrally with a beveled or inclined border portion that consists of substantially separate sections, as designated by the numeral 10. Radially disposed channels or depressions 11 are provided for separating the various sections 10,

as best shown in Fig. 3. It is to be understood that these channels or depressions 11, while they are below the substantially curved top surfaces of the sections 10, are actually positioned on an incline to the centrally positioned flat portion 8. Entirely embedded within the lift 7 and positioned at the four corners 12 of the flat portion 8 are metallic washers 13 that are provided with suitable apertures for receiving the securing nails 14 therein, further washers being positioned substantially centrally of the two sections 10 forming the rear portion of the lift.

Referring particularly to Fig. 6, where there is shown a modified form of the invention, it will be seen that the upper face of the lift is provided with a triangularly-shaped central flat portion 8^a which is outlined by the edges 9^a, as shown. Projecting outwardly from these edges 9^a are formed sections 10^a that collectively constitute a beveled or inclined border entirely encircling the triangularly-shaped flat central portion 8^a. Radially extending channels or grooves 7^a extend from the three points 12^a formed by the central portion 8^a to the peripheral edge of the lift and are provided for distinctly separating the various sections 10^a. It will be seen in this form of the invention that one of the channels or depressions 11^a is positioned at the forward end of the heel and extends substantially longitudinally of the same. Washers 13 similar to those shown in the form described above are provided at the three points 12^a formed by the triangularly-shaped central flat portion 8^a and are for the same purpose as described above.

Referring particularly to Fig. 7 there is shown a modified form of heel lift that is very similar to the one shown in Fig. 6, the difference being that the centrally positioned triangularly-shaped flat portion 15 is exactly reverse to the flat portion 8^a. The inclined beveled border portion consists of the separate sections 16 that are formed by the channels or depressions 17 which extend radially from the three points 19 formed by the triangular portion 15. Metallic washers 13 are provided at the three points 19 formed by the triangularly-shaped central flat portion 15 while additional washers are positioned substantially centrally of the border sections 16 forming opposite sides of the heel lift, the said washers being adapted for the purpose set forth in the description

of the forms described above. In this form the longitudinally extending channel or depression 17 is positioned at the rear end of the lift, as shown.

- In applying the various forms of lifts shown in Figs. 1-7, to a shoe heel, the same are first positioned as shown in Fig. 1 with the fastening nails 14 partly driven into the shoe heel 5. It is to be understood, with the 10 lifts in this position, that the centrally positioned flat portions will be substantially parallel with the under face of the heel while the central portion of the peripheral edge of each section forming the inclined or 15 beveled border will be positioned in engagement with the under face of the heel while the separating channels or depressions will be slightly spaced therefrom. The positioning of the fastening nails at the various corners of the centrally positioned flat portions 20 will draw the same into a position flatly engaging the shoe heel when the nails are driven home. The various sections forming the inclined or beveled border around the 25 centrally positioned flat portion will have a tendency to spring away from the under face of the heel with the result that the peripheral edges of the lifts will be retained against the said heel to prevent dirt or the 30 like from lodging between the lift and the heel. The bordering edges of the centrally positioned flat portions and the radially extending channels or depressions will create 35 dividing lines between the various sections and the centrally positioned flat portion,

with the result that the force tending to push the lift away from the shoe heel will be divided into several distinct and separate portions acting upon the said sections respectively.

It is to be understood that the forms of this invention herewith shown and described are to be taken as the preferred examples of the same, and that various changes in the shape, size, and arrangement of parts 45 may be resorted to without departing from the spirit of the invention or scope of the subjoined claim.

Having thus described the invention, I 50 claim:—

A cushion shoe heel comprising a resilient body having a flat central portion of polygonal form in plan, and a continuous series of relatively wide integral marginal portions extending at an upward and outward inclination from the edges of said polygonal central portion, the adjacent end edges of said marginal portions being integrally joined on straight lines radiating from the corners of said polygonal central 60 portion, the heel having nail holes at said corners to facilitate passing of nails or the like through the resilient body at the corners of the polygonal central portion to secure the cushion heel to and flatten it in engagement with the under surface of the usual heel of a shoe.

In testimony whereof I affix my signature.

ANTONIO PENTIFALLO.
